SANCTUARY LAMP

Oscar D. Guilfoil, Syracuse, N. Y., assignor to
 Will & Baumer Candle Company, Inc., Syracuse, N. Y., a corporation of New York

Application October 30, 1935, Serial No. 47,435

10 Claims. (Cl. 240—13)

My invention relates to improvements in sanctuary lamps designed particularly for use in churches and for other religious purposes.

An object of my invention is to provide an improved sanctuary lamp which is economical to operate and which conserves the candle fuel and enables burning of substantially all of the candle material.

Another object of my invention is to provide a supporting frame for a sanctuary lamp which is of novel design and adapted to retain the chimney and base of the sanctuary lamp in assembled relationship.

My invention further contemplates the provision of a sanctuary lamp of the follower type in which the follower has depending side walls closely embracing the side walls of the candle and of a depth sufficient to retain the candle material within the confines of the follower when the follower comes to rest upon its seat.

My invention further contemplates the provision of a glass insert for the base of a sanctuary lamp of the follower type which is adapted to receive the candle and is provided with apertures, whereby that portion of the melted candle material which has seeped between the lower edge of the follower and the glass insert upon which the follower seats may seep back into the glass insert and be consumed during the burning of the candle.

Other objects and advantages will be more apparent from the following description when taken in connection with the accompanying drawing, in which:

Figure 1 is a view showing the sanctuary lamp in assembled condition.

Figure 2 is a view taken on the line 2—2 of Figure 1.

Figure 3 is a view taken on the line 3—3 of Figure 2.

The candle C, adapted to be used in the sanctuary lamp of my invention, is an elongated large diameter candle made of slow-burning wax provided at its lower end with inwardly converging side walls 11 forming a base for the candle. The base of the candle is adapted to be received in an insert 12 preferably made of glass. The glass used for the base is preferably a glass resistant to heat and is shaped to conform to the shape of the base 11 of the candle. The insert has an annular vertical wall 13, an inwardly and downwardly extending wall 14 and a bottom 16. The side walls 12 of the insert near the bottom 16 are provided with ap-

tures 17, preferably four in number, for a purpose to be later described.

The bottom 16 of the insert rests upon the bottom 18 of a cup-shaped base 19 preferably made of ruby glass. The base 19 is spaced at the sides from the insert 13, as shown in the drawing, and has vertical upwardly extending side walls 21 which extend upwardly concentric with the candle and concentric with the vertical sides 13 of the insert. A globe or chimney 22 for the candle, preferably made of ruby glass, rests upon the annular rim of the base 19 and extends upwardly concentric with the candle. The upper end of the chimney is open and is flared outwardly, as indicated at 24.

The upper end of the candle C has a sloping surface 26 which is adapted to receive a sloping surface 27 formed in a candle follower 28 which is preferably made of glass highly resistant to heat. The upper end of the follower 20 is bent outwardly at 29 so as to provide a flaring mouth 31 for retaining the melted candle material, when the candle is burning, in a pool at the top of the chimney. The sloping surface 27 of the follower engages the sloping surface 25 26 of the candle in a manner such that a seal is provided for preventing leakage of the candle material downwardly along the sides of the candle. The follower 28 is provided with a depending skirt 32 which is slightly larger in diameter than the diameter of the candle so that the follower may be supported entirely by the top of the candle and move downwardly as the candle burns.

A frame for the sanctuary lamp, generally indicated by the numeral 30, is provided for holding the chimney 22 and the cup-shaped base 19 in assembled relationship and comprises three upwardly extending members 33 closely embracing the side walls of the chimney and the base.

An annular band 34, integral with the members 33, encircles the chimney 22 at the top of the frame and a second band 36, also integral with the members 33, embraces the chimney 45 and base 19 at the meeting point of the base and the chimney. The band 36 serves to retain the chimney against accidental displacement with respect to the base and serves to cover up the meeting edges of the chimney and base. A third annular band 37 is provided at the bottom of the frame. A base 38 having suitable supporting feet 39 is provided for the frame, the feet 39 being secured by screws to the base in line with the members 33. The entire frame is 55

preferably made of brass or any other suitable metal and is ornamented in a distinctive manner so that the sanctuary lamp will present a pleasing appearance. If desired, suitable ornaments 5 41 may be placed at the top of each of the vertical members 33.

When the sanctuary lamp has been assembled, as shown in the drawing, and is lighted, the flame of the candle melts the wax at the top 10 thereof. The weight of the follower is sufficient so that it rests upon the sloping surface 26 of the candle and forms a seal to prevent leakage of the candle material downwardly along the sides of the candle thus retaining a pool of 15 melted candle material in the flaring mouth of the follower.

As the candle burns downwardly, the follower moves downwardly with the candle, the melted candle material being retained entirely by the 20 flaring mouth of the follower. The diameter of the depending skirt of the follower is such that when the candle has burned down near the lower end, the depending rim 42 seats upon the rim of the vertical side walls 13 of the glass insert 12. After the follower has seated upon the 25 insert 12, the continued burning of the candle causes the surface 26 of the candle to recede from the surface 27 of the follower so that a seal is no longer provided at this point. The 30 molten candle material then tends to flow downwardly into the slight annular space that exists between the side walls of the candle and the depending skirt of the follower. This candle material flows downwardly in this space a distance, dependent upon external temperature 35 conditions, and after it is a sufficient distance away from the heat of the flame of the candle, tends to solidify. The candle material, as it solidifies, builds up an annular ring of solid 40 candle material extending around the candle between the side walls of the candle and on the inner surface of the depending skirt of the follower. This annular ring of solidified candle material retains the molten candle material 45 in a pool at the top of the candle. This condition is indicated by dotted lines in Figure 2 where the level of the molten candle material is indicated by the numeral 44 and the top of the solid candle by the numeral 45. As the candle 50 continues to burn downwardly, this annular ring of solid candle material moves downwardly in accordance with the burning of the candle.

When the candle has burned downwardly to a certain point, dependent upon external temperature 55 conditions, the molten candle material seeps between the depending rim 42 of the follower and the upper edge of the side walls 13 of the insert. When this seepage occurs the melted candle material drops into the annular 60 space between the base and the insert, solidifies, and builds up in the base until the level of molten candle material on the outside of the follower is the same as that on the inside of the follower. The depth of the skirt 32 of the follower and the height of the side walls 21 of the base 65 19 are, however, made sufficient that even under the most extreme temperature conditions, the candle material will not flow into the cup-shaped base until the level of the molten candle 70 material at the top of the candle is below the upper edge of the cup-shaped base or at least until the level of the molten candle material at the top of the candle is such that it is only slightly higher than the upper edge of the base 75 so that when seepage occurs and the molten

candle material has sought its level the height of the molten candle material, both inside and outside of the follower, will be below the upper edge of the cup-shaped base.

The continued burning of the candle causes 5 the level of candle material, both inside and outside of the follower, to drop and the solidified candle material in the space between the insert and the cup-shaped holder remelts and flows through the apertures 17 into the insert 10 where it is consumed by the flame of the candle. Thus, substantially the entire candle material is consumed during the burning of the candle, only a slight residue remaining which may be readily cleaned out upon separation of the 15 chimney 22 from the base 19.

It will be apparent that I have provided a novel sanctuary lamp which acts to conserve the candle and insures the complete burning of substantially all the candle material. It will further be apparent that various modifications and changes may be made in the form and relation 20 of parts without departing from the spirit of the appended claims.

I claim:

1. In a sanctuary lamp, a cup-shaped base and a chimney for enclosing the candle, said chimney resting upon the upper edge of said cup-shaped base, and a frame for supporting said base and chimney in assembled relation- 30 ship.

2. In a sanctuary lamp, a cup-shaped base, an insert for receiving a candle supported in said base, said insert having a plurality of perforations in the bottom thereof for enabling the 35 melted candle material flowing into said cup-shaped base to seep back into said insert.

3. In a sanctuary lamp, a cup-shaped base, an insert for receiving a candle supported in said base, a follower mounted on the top of the candle adapted to move downwardly with the candle as the candle burns and adapted to seat on the 40 insert when the candle has burned down near the bottom, said insert having a plurality of apertures therein for enabling the candle material which seeps between the bottom of the follower and the insert to flow back into the 45 insert.

4. In a sanctuary lamp, a cup-shaped base, a candle holder for supporting the candle 50 mounted in said cup-shaped base, a follower mounted on the top of the candle and having a depending skirt closely surrounding the side walls of the candle, said follower being adapted to retain the melted candle material at the top 55 of the candle, move downwardly as the candle burns and seat upon the candle holder when the candle has burned down near the bottom, said depending skirt being in such intimate relationship with the candle that when the follower 60 has seated on said candle holder the melted candle material which flows downwardly below the top of the solidified portion of the candle solidifies between the walls of the candle and said depending skirt whereby a pool of melted 65 candle material is retained on the top of the candle until the level of the candle material inside the follower is below the rim of the cup-shaped base.

5. In a sanctuary lamp, a cup-shaped base, 70 a candle holder for supporting the candle mounted in said cup-shaped base, a follower mounted on the top of the candle and having a depending skirt closely surrounding the side walls of the candle, said follower being adapted 75

to retain the melted candle material at the top of the candle, move downwardly as the candle burns and seat upon the candle holder when the candle has burned down near the bottom, 5 said depending skirt being in such intimate relationship with the candle that when the follower has seated on said candle holder the melted candle material which flows downwardly below the top of the solidified portion of the candle 10 solidifies between the walls of the candle and said depending skirt whereby a pool of melted candle material is retained on the top of the candle until the level of the candle material inside the follower is below the rim of the cup-shaped base, and means for enabling the candle material which seeps between the lower edge of said depending skirt and said candle holder into said cup-shaped base to seep back into said candle holder to be consumed during the burning 15 of the candle.

6. In a sanctuary lamp, a cup-shaped base, a candle holder for receiving a candle supported in said base, a chimney supported by the base and extending upward concentric with the candle, 20 means for preventing leakage of candle material into the base at least until the candle has burned almost to its bottom, said candle holder having an opening near the bottom thereof to enable candle material flowing into the base to seep back into the candle holder.

7. In a sanctuary lamp, a cup-shaped base, a candle holder for receiving a candle supported in said base, a chimney supported by the base and extending upward concentric with the candle, 25 a follower mounted on the top of the candle 30

adapted to retain melted candle material on top of the candle and to move downward with the candle as the candle burns and seat upon said candle holder, said candle holder having an opening near the bottom thereof to enable candle material flowing into the base to seep back into the candle holder. 5

8. In a sanctuary lamp, a cup-shaped base and a chimney for enclosing the candle, said chimney resting upon the upper edge of said base, and 10 a frame for supporting said base and chimney in assembled relationship, said frame having a band encircling said base and chimney at their meeting edges.

9. In a sanctuary lamp, a cup-shaped base, a 15 chimney for enclosing the candle, said base and said chimney having substantially vertical side walls of the same external diameter enabling the chimney to be seated upon the upper edge of the cup-shaped base and present a continuous 20 outer wall of base and chimney, and a frame for retaining said base and chimney in said relationship.

10. In a sanctuary lamp, a cup-shaped base, a 25 chimney for enclosing the candle, said base and said chimney having substantially vertical side walls of the same external diameter enabling the chimney to be seated upon the upper edge of the cup-shaped base and present a continuous 30 outer wall of base and chimney, and a frame retaining said base and chimney in said relationship, said frame having a band encircling the base and chimney at their meeting edges.
